UNITED STATES PATENT OFFICE.

DORSEY F. ASBURY, OF BROOMES ISLAND, MARYLAND.

METHOD OF AND MEANS FOR PREVENTING LEAKAGE.

Application filed February 19, 1925. Serial No. 10,293.

My invention relates to a method of and means for preventing leakage of fluid past a member movable in a passageway between high and low pressure fluid chambers, to 5 which end it consists in the various improvements over existing methods and means for the same purpose as will be more fully described hereinafter in connection with the accompanying drawings and particularly defined in the appended claims.

In the drawings, wherein like characters of reference denote corresponding parts in the different views:—

Fig. 1 is a vertical section through a portion of an internal combustion engine showing one status of a means for accomplishing my purpose; and

Fig. 2, a view similar to Fig. 1 showing another status of the means for accomplishing my purpose.

By reference to the drawings it will be observed that I have illustrated an internal combustion engine equipped with a valve mechanism of the same general type constituting the subject matter of my prior Patent 1,388,520, and that I have shown my present invention in one instance as designed to prevent leakage of relatively high pressure exhaust gases past the barrel or piston valve of such mechanism into the relatively low pressure intake gases, and in another instance as designed to prevent leakage of relatively high pressure gases of explosion past the piston of the engine into the base thereof which is subject to relative low pressure. I desire to point out, however, that these disclosures are merely for the purpose of illustrating specific utilitites of my invention and should so be construed, as manifestly the invention may be found to be equally useful in other mechanisms presenting substantially the same problems with respect to the prevention of leakage of fluids as are encountered in the internal combustion engine art in the particular instances mentioned.

The engine illustrated is of the "valve-in-head" type and includes essentially a cylinder 10, a piston 11, reciprocal therein, a passage or chamber 12 for the admission of intake gases, a passage or chamber 13 for carrying off exhaust gases, and a passageway 14, between said passage or chambers 12 and 13, within which is arranged a valve mechanism for controlling the intake and exhaust

of gases through a port 15 to and from the cylinder 10.

As my aforesaid prior Patent 1,388,520 fully describes the essential structural characteristics and mode of operation of the valve mechanism herein illustrated, it is deemed unnecessary to again describe the same in detail, other than to point out that the barrel or piston valve 16, which is slideable within passageway 14, is held normally to its seat surrounding port 15 by a coil spring 17, and is moved to the position of Fig. 2 under the influence of the pressure and velocity of exhaust gases when the puppet valve 18 is opened. A clapper valve 19 seats against the inner end of barrel or piston valve 16 to prevent exhaust gases from traveling through the latter into the intake passage or chamber 12, and this valve also operates to control the intake of gases from passage or chamber 12 into the cylinder 10, all as is well known. Thus it is evident that during exhaust the inner end of the barrel or piston valve is subjected to the relatively high pressure of the exhaust gases present in passage or chamber 13, while the outer end thereof is subjected only to the relatively low pressure of the intake gases present in passage or chamber 12, and under such conditions there is a very pronounced tendency of the high pressure exhaust gases to leak from passage or chamber 13 past the barrel or piston valve into the intake passage or chamber 12 due to the difference in pressure existing in said chambers. To prevent such leakage

I form the outer end of the barrel or piston valve 16, that is, the end thereof which is subjected to the low pressure intake gases, as the male element of a dash-pot and arrange within the passage way 14 a member 20 formed as the female element of said dash pot, the arrangement being such that when the barrel or piston valve is closed, that is, at its limit of inward movement, as shown in Fig. 1, the male element of said dash pot is disposed out of the female element so that intake gases may fill the latter, while on the other hand, when the barrel or piston valve is opened by the influence of the pressure and velocity of exhaust gases, the male dash pot element is moved into the female element with the result that the intake gases therein are compressed. Around the outside of the barrel or piston valve 16, intermediate its ends, is formed an annular recess 21, while in

the wall defining passageway 14 is formed one or more grooves 22 leading from the bottom of the female dash pot element inward towards the barrel or piston valve 16, said groove or grooves being of such length as to be overlapped by the annular recesses 21 when the male dash pot element has almost reached the bottom of the female dash pot element, so that the intake gases compressed in said dash pot are forced under relatively high pressure into said annular recess where they act to balance the tendency of the high pressure exhaust gases to pass by the barrel or piston valve into the intake passage or chamber, and where they are trapped due to blanking of said annular recess and said grooves when the male element is moved outward with respect to the female element by the spring 17 as the exhaust pressure vanishes, so as to act to balance the initial tendency of the exhaust gases to leak past the barrel or piston valve into the intake passage when exhaust again takes place.

To prevent leakage of relatively high pressure gases of explosion within cylinder 10 past piston 11 into the base of the engine which is subject to relatively low pressure, I utilize substantially the same method and means described in connection with valve 16; that is, I form the open end of the piston as the female element of a dash pot and arranged within the cylinder, for cooperation with said female element, a male element 23, while in the wall of the piston I form an annular recess 24 and provide in the wall of the cylinder a groove or grooves 25 of such length as to overlap said recess when the male dash pot element has almost reached the bottom of the female element. The only difference between this arrangement and the arrangement described in connection with barrel or piston valve 16 is that in the first instance the piston carries the male element of the dash pot while in the second instance the piston carries the female element of the dash pot. However, the mode of operation and the results achieved are the same in each instance: As the piston nears the completion of its down stroke the female element operates with the male element of the dash pot to compress a portion of the low pressure fluid in the base of the engine and force it under high pressure through the groove or grooves 25 into recess 24 where it acts to balance the tendency of the high pressure explosive gases above the piston to pass by the latter into the base. Upon upward movement of the piston the gases under high pressure are trapped in the recess to balance the tendency of the initial high pressure gases above the piston to escape past the latter when the next explosion occurs in the cylinder.

It will be observed that the fluid entering the recesses 21 and 24 serves to lubricate the

sliding surfaces of the barrel valve 16 and piston 11, respectively, as well as the walls of engine with which they engage; also that the dash pots serve to cushion movement of both the barrel valve and piston in one direction, and that said dash pots are self-cleaning due to the inclination of the bottom of the female element in one instance and to the inclination of the end of the male element in the other instance. It will further be apparent that instead of forming the recesses 21, 24 in the piston elements they might readily be formed in the walls surrounding the piston element should such an arrangement for any reason be found desirable.

I claim:

1. Means to prevent leakage of fluid past a member reciprocal in a passageway between high and low pressure fluid chambers, including means operated by movement of said member in the direction of said low pressure chamber to raise the pressure of a portion of the fluid in the low pressure chamber, and means whereby the fluid compressed by said first named means is forced past a portion of said member in the direction of the high pressure fluid chamber to balance the tendency of fluid in the high pressure chamber to pass by said member into the low pressure chamber.

2. In mechanism of the class described, a cylinder between high and low pressure fluid chambers, a reciprocal piston slidable in said cylinder, means defining a cavity opening to the sliding faces of the cylinder and piston, a dash pot within which a portion of the fluid in the low pressure chamber is adapted to be compressed by movement of said piston to cushion the latter, and means placing said dash pot in communication with said cavity as the piston approaches the end of its stroke in one direction to reduce the pressure in said dash pot, said means operating to cut off such communication when the piston is moved a predetermined distance in the other direction whereby the pressure in said cavity is retained therein to balance the tendency of fluid in the high pressure chamber to pass by said piston into the low pressure chamber.

3. In mechanism of the class described, a cylinder, a piston reciprocal in said cylinder, and a dash pot within which fluid is adapted to be compressed by movement of said piston to cushion the same, said dash pot including a chamber element and a plunger element movable into and out of the same, the end of said plunger element being inclined whereby matter will slide off the same when it is out of the chamber member.

4. In mechanism of the class described, a cylinder, a piston slidable therein, a dash pot

- plunger element carried by said piston and a dash pot chamber element with which said plunger element cooperates to cushion movement of said piston, means defining a cavity 5 opening to the sliding faces of the cylinder and piston intermediate the ends of the latter in any position thereof within the cylinder, and means defining a by-pass constantly in communication with said dash pot and cut 10 off from and placed in communication with said cavity by movements of said piston.
5. Means to prevent leakage of fluid past a member reciprocal in a passageway between high and low pressure fluid chambers 15 comprising a dash pot composed of cooperating male and female elements one of which is carried by said member and the other of which has a fixed location within the low pressure chamber, said elements being arranged with respect to one another so that movement of said reciprocal member in the direction of the low pressure chamber will cause them to coact to compress a portion of the fluid in said low pressure chamber, and 20 means whereby the low pressure fluid compressed by said dash pot elements is caused to balance the tendency of fluid in the high pressure chamber to escape past said reciprocal member into the low pressure chamber.
- 25
6. Means to prevent leakage of fluid past a member reciprocal in a passageway between high and low pressure fluid chambers comprising a dash pot, means whereby movement of said member in the direction of said low pressure chamber causes said dash 30 pot to exert a compressive action on fluid contained therein, and means whereby the fluid compressed by said dash pot is caused to balance the tendency of fluid in said high pressure chamber to escape past said reciprocal member into said low pressure chamber. 35
7. In mechanism of the class described, a cylinder between high and low pressure fluid chambers, a reciprocal piston slidable within said cylinder, means defining a cavity opening to the sliding faces of said cylinder and piston, means operated by movement of said piston to compress a portion of the fluid in said low pressure fluid chamber, and means whereby the fluid compressed by said compressing means is conducted to said cavity to balance the tendency of fluid in the high pressure chamber to escape past said piston 40 into the low pressure chamber. 45
- 50

In testimony whereof I hereunto affix my 55
signature.

DORSEY F. ASBURY.
